CAST METAL CAR BODY

Filed May 3, 1929

UNITED STATES PATENT OFFICE

ALBERT W. ALBRECHT, OF UNIVERSITY CITY, MISSOURI

CAST-METAL CAR BODY

Application filed May 3, 1929. Serial No. 360,081.

This invention relates to a cast-metal car body, and an object is to provide a car body comprising a unitary casting so that the car body may be made of cast steel or its equivalent so as to dispense with the necessity of using rivets or bolts for fasteners, while at the same time the weight is not substantially increased, but greater strength and durability is obtained.

Another object of the invention is to provide a car body comprising a cast unitary floor provided with integral longitudinal and transverse reinforcing ribs and flanges and with means at the ends for supporting the coupling devices.

Other objects will appear from the following description, reference being made to the accompanying drawing in which

Fig. 1 is a top plan view of my improved car body.

Fig. 2 is an under side plan view of my improved car body.

Fig. 3 is a side elevation.

As shown in the drawing my improved car body is in the form of a unitary casting comprising a floor wall 1 having a smooth upper surface and of less thickness than the usual floors of flat cars of the type shown. The floor 1 is a unitary casting extending the full length and width of the car. The upper surface of the floor 1 is unobstructed and smooth from end to end and from edge to edge.

Along each longitudinal side edge of the car body a depending reinforcing flange 2 is formed, the same being an integral part of the casting of which the car body is made. This flange 2 is relatively thin and comprises substantially less metal than the side supporting members of the usual car bodies. For, by making the car body of a unitary structure a very considerable saving of material is obtained.

Along the under side of the car body and spaced equidistant from the side edges thereof of a pair of spaced longitudinal depending ribs or flanges 3 are formed. These flanges 3 strengthen the intermediate portion of the car body longitudinally and they displace the usual reinforcements and supporting

beams comprised in flat cars of ordinary construction having wood floors. The ends of these flanges 3 terminate at formations provided for the connecting pins for attaching the car bodies to the supporting truck structure. The formations shown comprise depending bosses 4 having holes 5 therethrough adapted to receive the bolts or pins for connecting the car body with the supporting trucks. From the outer side of each of the bosses 4 a pair of parallel depending flanges 6 extend to the adjacent end of the car body and it is between these flanges 6 that appropriate coupling devices are to be mounted so that the bosses 4 and the longitudinal ribs 3 or flanges 3 will resist and withstand the longitudinal strains to which a car body is subjected. These flanges 6 extend to the adjacent ends of the car body. Further, from each side of each of the bosses 4 a pair of depending flanges 7 extend to integral union with the depending side flanges 2. From the corners of the bosses 4 between the flanges 6 and the flanges 7 a depending rib or flange 8 extends to the end corners of the car body so that the ends of the car body beyond the flanges 7 are strengthened and reinforced and this strengthening and reinforcement is increased by a depending transverse flange 9 along each end of the car body extending from integral union with the ends of the flanges 6 to integral union with the ends of the flanges 8 and 2. Thus no ordinary strains to which the car body is subjected can bend or distort the ends of the car body, even though the coupling devices are made to exert very great lateral or torsional strains. Corner abutment bumpers 10 are formed at each corner of the car body on the transverse depending flanges 9.

The intermediate portion of the car body is transversely strengthened and supported by depending flanges 11 extending transversely across the car body to integral union with the side flanges 2. These flanges 11 cross the spaces between the flanges 2 and 3 and also cross the spaces between the flanges 3, as will readily be understood by reference to Fig. 2.

In the embodiment shown my improved car body is formed with integral stake

5   sockets 12 which are formed in connection with the side flanges 2 and which extend laterally therefrom. These stake sockets are opposite the ends of the flanges 11 so that there is sufficient bracing and strengthening thereof to resist any of the strains within the capacity of the car. The sockets 12 do not extend above the upper surface of the floor 1. On the contrary, the upper ends of 10   the sockets 12 are approximately even with the upper surface of the floor 1, so that said sockets do not constitute any obstruction along either side of the floor.

15   At the ends of the spaces between the flanges 6 appropriate openings 13 are provided to receive the proper parts of the coupling devices.

20   From the foregoing it must be clear that my invention is a car body of highly simplified and of very strong and durable construction. Being made in a unitary structure and strengthened and reinforced substantially in the manner described, this car body is capable of withstanding all strains to 25   which any car should be subjected.

I am aware that the construction may be varied within equivalent limits without departure from the nature and principle of the invention.

30   I claim:—

35   1. A unitary cast-metal car body comprising a single casting including a floor having an upper surface that is unobstructed throughout its width, two depending side flanges extending longitudinally along the side edges of said floor, flanges integral with the under side of said floor at the ends thereof for receiving couplings, a series of stake sockets along each of said side flanges 40   terminating near the plane of the upper surface of the floor and leaving the lateral edges of the floor unobstructed, bosses depending from the underside of said floor and having holes for receiving pins, flanges depending from said floor and having their ends integrally united with said bosses, and a series 45   of transverse flanges depending from said floor and intersecting said first named flanges and having their ends opposite said stake 50   sockets.

55   2. A unitary cast-metal car body comprising a single casting including a floor having a smooth upper surface, two depending side flanges extending longitudinally along the side edges of said floor, flanges integral with the under side of said floor at the ends thereof for receiving couplings, a series of stake sockets along each of said side flanges, bosses depending from the under 60   side of said floor and having holes for receiving pins, flanges depending from said floor and having their ends integrally united with said bosses, a series of transverse flanges depending from said floor and intersecting said first named flanges and having their ends 65

70   opposite said stake sockets and flanges having their inner ends integral with said bosses and extending therefrom, to integral union with said side flanges at the corners of said floor.

75   3. A unitary cast-metal car body comprising a single casting including a floor extending the full length and width of the car body and having an upper surface that is unobstructed between its side edges, two depending longitudinal flanges integral with the lower side of the car body and spaced approximately equi-distant from the side edges thereof, supporting bosses integral with the under side of the floor at the ends of said flanges and having integral connection with said flanges, a series of stake sockets along each outer side edge of said floor, and depending flanges extending from integral connection with said bosses to the end of the car 85   body for confining coupling devices between them.

90   4. A unitary cast-metal car body comprising a single casting including a floor extending the full length and width of the car body and having an upper surface that is unobstructed between its side edges, two depending longitudinal flanges integral with the lower side of the car body and spaced approximately equi-distant from the side edges 95   thereof, supporting bosses integral with the under side of the floor at the ends of said flanges and having integral connection with said flanges, depending flanges extending from integral connection with said bosses to the end of the car body for confining coupling devices between them, flanges integral with the floor extending from integral connection with said bosses to the side edges of the car body, marginal flanges integral with the end 100   and with the side edges of the car body connecting the ends of said second named flanges with the ends of said third named flanges, and a series of stake sockets integral with said flanges that are at the side edges of said car 105   body.

110   5. A unitary cast-metal car body comprising a single casting forming a floor that has its upper surface unobstructed from edge to edge, flanges integral with the underside of said floor at the ends thereof for receiving couplings, a series of stake sockets extending downwardly along each side edge of said floor and having their upper ends approximately in the plane of the upper surface of the floor 115   and leaving the lateral edges of the floor unobstructed, and integrally formed bosses on the under face of said floor forming means for connecting the car body with car trucks.

120   6. A unitary cast-metal car body comprising a single casting forming a floor that has its upper surface unobstructed from edge to edge, flanges integral with the underside of said floor at the ends thereof for receiving couplings, a series of stake sockets extending 125

downwardly along each side edge of said floor and having their upper ends located relative to the upper surface of the floor whereby the lateral edges of the floor are left unobstructed, integrally formed bosses on the under face of said floor forming means for connecting the car body with car trucks, and flanges depending from said floor and having ends integrally united with said bosses.
